UNITED STATES PATENT OFFICE.

ERNST G. K. ANDERSON, OF CHICAGO, ILLINOIS, ASSIGNOR TO APPLETON ELECTRIC COMPANY, A CORPORATION OF ILLINOIS.

DEMOUNTABLE SPOTLAMP WITH EXTENSION CORD.

Application filed February 10, 1926. Serial No. 87,287.

In the usual so-called spot lamp that is removably mounted on its support and provided with a reel on which a long extension cord is wound, the current flowing to the lamp at all times passes throughout the entire length of the cord, thus introducing a non-useful resistance in the circuit. The primary object of the present invention is to produce a simple and novel lamp of this kind in which a shunt of negligible resistance will be placed across the long cord on the reel when the spot lamp is mounted for ordinary use on its support; the shunt being preferably connected automatically when the lamp is placed in position on its support.

A further object of the present invention is to improve generally the construction of spot lamps in the casings of which are mounted reels for extension cords.

20 The various features of novelty whereby my invention is characterized will herein-after be pointed out with particularity in the claims; but, for a full understanding of my invention and of its objects and advantages, reference may be had to the following detailed description taken in connection with the accompanying drawings, wherein:

Figure 1 is a central vertical section through a spot lamp embodying my improvements, including the immediate supporting means for the lamp; Fig. 2 is a central vertical section, on an enlarged scale, through a portion of the lamp support; Fig. 3 is a top plan view of the lower stationary part of the support shown in Fig. 2, the upper turn-table member being omitted, and the vertical pinion for rotating the lamp being shown in section; Fig. 4 is a top plan view of the mechanism shown in Fig. 2; Fig. 5 is an edge view of the plates or discs secured on the upper end of the long vertical pinion, showing one of the terminals of the extension cord; and Fig. 6 is a section taken approximately on line 6—6 of Fig. 4.

45 The spot lamp shown in the drawings is similar to that disclosed in my prior application, Serial Number 745,789 filed October 25, 1924, and need not therefore be described, other than briefly. Except to the extent hereinafter pointed out, the details of the lamp structure form no part of the present invention and may be varied at will.

Referring to the drawings, 1 represents a sheet metal, rearwardly-coned casing, open at its front end, 2 is the usual reflector, 3 is

the usual crown lens, and 4 is the usual trough-shaped ring for holding the parts together.

The cord-receiving reel is located in the casing in rear of the reflector and between it and the rewinding spring 5. The spring is housed in a cup-shaped barrel 6 having its mouth directed rearwardly and closed by a plate 7. The inner end of the spring is attached to a metal sleeve 8 co-axial with the lamp casing, while the outer end is fixed to the barrel. The reflector has a short sleeve-like part 9 extending rearwardly at the center and fitted into the front end of the sleeve 8. Between the reflector and the spring barrel is a cup-shaped sheet metal member 10 having its mouth directed forwardly and its sides extending forwardly from the bottom wall of the cup in the form of a cylinder and then flaring laterally to follow the configuration of the reflector. The member 10 is interlocked with the spring barrel by means of lugs or ears 11 struck up from the latter and passing through holes in the bottom wall of the former. A spacing ring 12 is placed on the sleeve 8 between the bottom of the cup 10 and the reflector. The extension cord 13 is wound about the member 10, the front wall of the spring barrel forming the rear wall or side of the trough in which the cord lies.

Within the sleeve 8 is a lamp socket 14 of any usual or suitable construction to receive the base 15 of an electric lamp; the socket being slidable lengthwise and being held against rotation by a screw 33 passing through the sleeve 8 and extending into an elongated slot 34 in the socket.

Behind and coaxial with the sleeve 8 is a post 16 of insulating material between which and the rear wall of the lamp casing is placed a helical spring 17. A screw 18 passes through the apex of the casing and into the rear end of the post, the screw being free to move lengthwise with respect to the lamp casing. The spring 17 is placed under an initial compression so as to hold the head of the screw yieldingly against the casing; thus permitting the post 16 and the lamp socket to be drawn rearwardly by the screw or pushed forward by the spring to focus the lamp. Into the front end of the post is screwed a metal plug 19 within which, and coaxial with which, is a sliding pin 20 having at its front end a head 21 for engagement

with the central contact or terminal on the lamp base. A spring 22 is arranged between the head of the pin and the front end of the plug, for the purpose of pressing the head of the pin against the lamp base. Surrounding the plug 19, directly in front of the post 16, is a metal disc 23 that may be made cup-shaped at the middle to fit over the end of the post. Directly in front of the disc 23 is 10 a metal fork 24 having in its upper end an opening through which the plug passes, and extending down toward the bottom of the lamp casing. In front of the fork 24, and between the same and the rear end of the sleeve 14, is a thick disc 25 of insulating material, and in front of this disc is a second smaller disc 26, also of insulating material, fitting into the rear end of the sleeve 14. The front end of the plug is enlarged in diameter to 20 form a head 27. When the parts are assembled and the plug is screwed into the post, the head engages with the disc 26, and presses this disc, the disc 25, the fork 24, and the disc 23 against the front end of the post.

25 One end of one of the conductors of the extension cord, as indicated at 28, is grounded to the plate 7 that closes the rear end of the spring barrel, while the corresponding end of the other conductor, as indicated at 29, 30 is fastened to a bracket 30 fastened at one end to the fork 24 by a screw 31 or otherwise, and supported from the plate 7, while insulated from the latter plate by means of insulation 32.

35 The lamp casing has an opening in the bottom near the front end thereof, and extending through this opening is a sleeve 35 of heavier metal than that of which the casing is made, the upper end of the sleeve being flanged laterally, as indicated at 36 to overlie the metal of the casing surrounding the opening; the sleeve being permanently fastened to the casing in any usual or suitable way. The immediate support for the lamp casing 40 is a turntable 37 having in the top, as best shown in Fig. 4, a curved slot 38 forming somewhat less than a complete circle; the sleeve 35 being adapted to rest in this slot. The sleeve, of course, has a section cut out of 45 one side so as to give it an angular length equal to that of the slot. A holding screw device 39, passing into one side of the turntable, serves to fasten the sleeve and the turntable together. When the lamp is to be 50 removed, the screw device 39 is backed off, permitting the sleeve to be lifted from the turntable. In order to prevent the screw device from being accidentally detached and mislaid, I prefer so to construct it that it can- 55 not become detached during ordinary use. To this end, I place in the side of the turntable an outwardly-opening comparatively deep socket 40 in the bottom of which is located the head 41 of the screw which engages 60 with the sleeve. Into the socket, outwardly

from the head 41, is pressed a ring 42 whose internal diameter is less than the diameter of the head 41. The head 41 has a central square projection 43 that fits into a socket 44 in the end of a stem 45 on the outer end 70 of which is a knob or head 46 for turning the same. A screw 47 passes axially through the stem 45 and into the projection 43. It will thus be seen that the screw device may be turned to fasten the lamp casing in place or 75 release it, but cannot be completely detached without first forcing the ring 42 out of the socket.

The turntable 37 has in the bottom an annular groove 50 that receives an annular ledge or rib 51 on the upper face of a supporting base 52. This supporting base is fixed to the end of a tubular stem 53 rotatable about its long axis in a stationary support 54. The turntable is held upon the 80 base by means of an elongated pinion 55 that extends vertically through the turntable and the base; the pinion being rotatable in the base and being preferably provided with a smooth lower headed portion 56 to form a bearing therefor in the base. The opening in the turntable, through which the pinion passes, is shaped to fit the pinion, so as to interlock the turntable and the pinion for rotation in unison with each other. Overlying the turntable and the upper end of the elongated pinion are a plurality of discs of 85 insulating material. There may conveniently be two thin discs 57 and an upper thick disc 58. A screw 59 passes through the discs and into the pinion. The discs 57 are cut away at one side to provide a recess to receive a combined contact and terminal in the form of a small metal plate 60 lying underneath the disc 58; the plate having an 90 eyelet 61 formed at one end and passing upwardly through the disc 58. At the other end of the plate is a clip 62 that passes up through a hole 63 in the disc 58. The conductor within the lamp casing, whose end 29 is fastened to the bracket 30, is fastened at 95 its other end to the clip 62. The corresponding end of the other conductor is fastened in any suitable way to the turntable so as to 100 make metallic contact therewith. In the 105 arrangement shown, the several discs above the turntable have a hole 64 cut through the same and there is a terminal 65 fastened to the turntable by a screw 66, passing up through the hole and having a clip 67 to 110 receive the conductor. The metal parts of the supports serve as one side of the electrical circuit to carry the current to the turntable and thence to one of the conductors in 115 the cord. The other side of the circuit is formed by a cord or cable that makes electrical connection with the contact plate 60 that will now be described.

Referring particularly to Figure 2, it will 120 be seen that there is a cable 70 extending 125

through the operating and supporting stem 53 into a chamber within the base 52. The end of this cable is fastened to a metal washer-like plate 71 mounted in the base 52 just below the central portion of the turntable, the connection being indicated at 72. In the arrangement shown, the plate 71 overlies a disc 73 of insulating material having in the center an opening considerably larger in diameter than the diameter of the pinion. The metal of the plate is flanged downwardly and then outwardly through this opening, as indicated at 74. Underneath the disc 73 is a second disc 75 that keeps the flanged central portion of the metal plate out of contact with the base. Overlying the marginal portions of the plate 71 is a ring 76 of insulating material that insures against metal contact between the plate and the turntable. The turntable has a hole 77 extending entirely through the same directly below the eyelet 61, this hole being considerably larger in diameter than the opening in the eyelet. Fitted within the hole 77 is a bushing 78 of insulating material. Within the bushing is a resilient contact piece which, in the arrangement shown, consists of a central sheet metal shell 79 within which are slidably arranged two thimbles 80 and 81, one projecting out of the top and the other out of the bottom. The inner ends of the thimbles are larger in diameter than the outer ends, and the ends of the shell 79 are flanged inwardly, thereby preventing complete separation of the thimbles from the shell. Within the shell is a long spring 82 whose ends rest in the thimbles. The parts are so proportioned that the lower thimble rests on the metal plate 71, while the upper thimble passes through the eyelet 61. The upper thimble makes metallic contact with the eyelet, and additional contact may be had through the engagement of the upper end of the shell 79 with the eyelet or the plate 60. This resilient contact rotates with the turntable, when the latter is turned, but always remains in contact with the plate 71 and the plate 60.

When the lamp is disconnected from the turntable and removed to a remote point, current is supplied to one of the conductors in the cord through the cable 70, the plate 71, the resilient contact, the plate 60 and the clip 62. When the lamp is being used in the normal way as a spotlight, the upper thimble 80 engages with a metal finger 84 mounted in the bottom of the lamp casing, but insulated therefrom by suitable insulating material 85; one end of the finger lying directly above the thimble. The finger 84 is part of a long strip of metal whose opposite end is bent upwardly to form a finger 86 that engages with the disc 23. Therefore when the lamp is in use as a spot lamp, the parts being assembled as shown in Fig. 1, the current for the lamp is not required to pass through any part of the

extension cord, but may flow directly from the contact thimble through the connected fingers 84 and 86 and the disc 23 to the plug 19 and then through the pin 20 to the central terminal of the lamp base. The returning current flows from the socket 14 directly to the metal parts of the lamp structure which make metallic contact with the turntable. However when the spot lamp is detached and removed to a remote point, both conductors of the extension cord come into play, current flowing through them and the lamp between the terminal clips 62 and 67.

In order to avoid subjecting the clips 62 and 67 to pulling stresses when the spot lamp is detached, the extension cord is passed through a hole in the top of a cap or shield 90 fastened upon the turntable and housing the plates 57 and 58. A knot 91 is tied in the extension cord underneath the shield, so that a pull on the cord is transmitted through the knot to the shield, and the fastenings for the ends of the conductors are unaffected. The shield has a slot 92 cut through the same to permit the thimble 80 to come in contact with the finger 84.

The turntable is rotated on the base 52 by means of two rack bars extending lengthwise through the tubular stem and lying on opposite sides of the pinion. Only one of these rack bars is shown, at 96, since this feature forms the subject of another application of even date herewith.

While the lamp casing, the reflector and the lens may take any desired forms, I prefer to make use of the spring 17 in the rear end of the casing to hold these parts together in a manner to prevent rattling, while permitting ready assembly and separation of the parts. The lamp casing has a flange 100 around its open front end, against which the reflector rests. The marginal portion of this flange is bent forwardly as indicated at 101, and the reflector also has a forwardly-projecting flange 102 that rests within the flange 101. The flanges 101 and 102 are not rolled down over the lens as is usual in this type of lamp, but the lens is simply set against the front of the reflector within the area bounded by the flange 102.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. In a spot lamp, a support, a lamp structure detachably connected to said support and provided with an extension cord, and means for placing a shunt around said cord when the lamp structure is on said support.
2. In a spot lamp, a support, a lamp struc-

- ture detachably connected to said support and provided with an extension cord to supply lamp current when the lamp structure is detached, and means for delivering current to the lamp independently of said cord when the lamp structure is connected to said support.
3. In a spot lamp a support, a lamp structure detachably connected to said support and provided with an extension cord to supply lamp current when the lamp structure is detached terminals on said support and current conductors independent of the cord leading from the lamp and adapted to engage with said terminals when the lamp structure is attached to the support.
4. In a spot lamp a metal support constituting a terminal, a lamp structure detachably connected to said support and provided with an extension cord to supply lamp current when the lamp structure is detached, a second terminal on and insulated from the support, said lamp structure having metal parts, independent of said cord to engage said second terminal and supply lamp current when said lamp structure is attached to the support.
5. In a spot lamp, a support, a lamp structure detachably connected to said support and provided with an extension cord to supply lamp current when the lamp structure is detached, a terminal on said support to which one of the conductors of said cord is connected, a yieldable contact piece in electrically-conductive relation to said terminal, and means independent of said conductor, and including an element adapted to engage said yieldable contact piece, to convey current therefrom to the lamp when the lamp structure is attached to said support.
6. In a spot lamp, a supporting base, a turntable on said base, a lamp structure, including an extension cord, detachably mounted on said turntable, terminals on said turntable to which the conductors of said extension cord are attached, and a shield connected to the turntable and overlying said terminals, the extension cord passing through an opening in said shield, and an enlargement on the cord below the shield to transmit a pull of the cord to the shield instead of to the terminals.
7. In a spot lamp, a supporting base, a turntable on said base, an annular contact plate on said base below the turntable, a terminal on top of the turntable, and a resilient contact piece extending downwardly from said terminal and resting on said contact plate.
8. In a spot lamp, a supporting base, a turntable on said base, an annular contact plate on the base below the turntable, a terminal plate at the top of the turntable, the terminal plate and the turntable having registering openings forming a vertical passage through the same, and an endwise yieldable contact piece arranged in said passage and pressed yieldingly against said terminal plate and said contact plates.
9. In a spot lamp, a supporting base, a turntable on said base, a lamp structure detachably connected to said turntable and provided with an extension cord, an annular contact plate on the base below said turntable, a terminal plate upon said turntable, one of the conductors of said cord being connected to said terminal plate, said terminal and said turntable having registering openings therethrough forming an upright passage, an endwise yieldable contact piece arranged in said passage and resting on said contact plate, and conducting means, independent of said conductor, for conveying current between said yieldable contact plate and said lamp when the lamp structure is attached to the turntable, said conducting means including a part adapted to engage the upper end of said contact piece.
10. In a spot lamp, having an extension cord, a turntable having an arc-shaped groove in the top, a lamp casing having a neck fitted into said groove, said turntable having in the side a socket, a holding screw for the casing passing through the socket and against said neck, an enlargement on the screw within the socket, and a part pressed into the socket outwardly of the said enlargement to engage with the latter and prevent removal of the screw.

In testimony whereof, I sign this specification.

ERNST G. K. ANDERSON.
